UNITED STATES PATENT OFFICE.

CHARLES WALTER LUND, OF WILLOWS, CALIFORNIA.

FRONT TRUCK FOR STREET-SWEEPING MACHINES.

1,418,154.

Specification of Letters Patent. Patented May 30, 1922.

Original application filed April 11, 1919, Serial No. 289,326. Divided and this application filed March 10, 1921. Serial No. 451,150.

To all whom it may concern:

Be it known that I, CHARLES W. LUND, a citizen of the United States, residing at Willows, in the county of Glenn and State 5 of California, have invented certain new and useful Improvements in Front Trucks for Street-Sweeping Machines; and I do declare the following to be a full, clear, and exact description of the invention, such as 10 will enable others skilled in the art to which it appertains to make and use the same.

This application is a division of my allowed U. S. application, Serial No. 289,326 filed April 11, 1919, and for a full 15 description of any details of construction not herein specifically described, reference may be had to this parent case.

The principal object of my invention is to provide a novel form of truck for supporting the front end of a street sweeping machine in such a manner as to permit the front wheels to drop into depressions and ride over projections without elevating or 20 lowering the entire front of the machine 25 and without exerting any torsional or twisting action thereon. In carrying out this object, I make use of several novel features of construction and unique arrangements of parts, as hereinafter fully described and 30 claimed, the descriptive matter being supplemented by the accompanying drawings.

Figure 1 is a side elevation of the street sweeping machine supported at its front end by the improved truck.

Figure 2 is a front elevation of the machine shown in Fig. 1.

Figure 3 is a side elevation partly broken away and in section, showing more clearly the construction of one of the trucks.

Figure 4 is a horizontal sectional view as indicated by line 4—4 of Fig. 3.

Figures 5 and 6 are vertical transverse sectional views as designated by lines 5—5 and 6—6 of Fig. 3.

In the drawings above briefly described, the numeral 1 designates the main body or housing of a motor driven street sweeping machine mounted on front and rear wheels 2 and 3, the front wheels being driven by 45 any preferred means such as chains 8, while suitable provision is made for steering the rear wheels 3.

The front wheels 2 are mounted in trucks 12, one of which is detailed in Figs. 3 to 6. 50 The front and rear brackets 13 and 13^a re-

spectively are rigidly secured to the sides of the housing 1 or to the frame of such housing as required, and each of said brackets includes a base 14, an inner side bar 15, and an outer side bar 16, the two bars 15 and 16 of each bracket being parallel throughout the greater part of their lengths and being by preference secured together at their upper ends as clearly shown in Figs. 2, 5 and 6. Two parallel horizontal bars 17 extend between the two brackets 13 and 13^a and contact with the inner sides of the bars 15 and 16, and by means of a pin 18 passing through the front ends of said bars 17 and the bracket 13, the former are pivoted. Spacing sleeves 19, mounted on tie bolts 20, are preferably provided between the front ends of the bars 17 as illustrated in Figs. 3 and 4 and in addition, a U-shaped spacing bar 21 is by preference employed, 75 the base of said bar being secured at 22 to the base 14 of the bracket 13, while the upturned ends 23 of said bar 21 are disposed for contact with the inner sides of the bars 17 as illustrated in Figs. 3, 4 and 6. The pin 18 passes through the ends 23 and said ends serve to guide the bars 17 in their pivotal movement upon the pin 18.

At their rear ends, the bars 17 are connected by a U-shaped bar 24 whose ends are riveted thereto at 25 (see Fig. 5). The bar 24 and the base 14 of the bracket 13^a are provided with aligned openings through which vertical bolts 26 extend, said bolts rising above the bars 17 and carrying an abutment 27. Coil springs 28 are interposed between the abutment 27 and the bar 24 and it will thus be seen that since the wheel 2 is mounted between the bars 17, vertical movement of said wheel with respect to the remainder of the machine is yieldably resisted by the springs 28. The front end of the machine is thus mounted in a manner to permit the front wheels to drop into depressions or ride over obstructions, without warping or exerting a torsional action on the entire machine. The rear end of the machine is supported yieldably by means of springs 29 from the axle 30 of the wheels 3, and these parts are preferably located beneath the rearwardly projecting portion 31 of the housing 1.

From the foregoing, taken in connection with the accompanying drawings, it will be seen that I have provided a comparatively 110

simple truck structure for carrying out the object of the invention, yet that the arrangement disclosed will be highly efficient and in every way desirable. Since excellent results are obtainable from the details disclosed, such details may be followed if desired, but within the scope of the invention as claimed, numerous changes may of course be made.

10 I claim:

1. In a truck, front and rear fixed brackets each including a base and parallel vertical side bars rising therefrom, a pair of parallel horizontal bars extending between said brackets and contacting with the inner sides of said side bars, a wheel mounted between said horizontal bars, the latter being pivoted to the side bars of one of said brackets, a transverse bar connecting the ends of said horizontal bars in the other bracket, a bolt rising from the base of said other bracket through an opening in said transverse bar, said bolt having an abutment spaced above said transverse bar, and a coiled spring interposed between said abutment and said transverse bar.

2. In a truck, front and rear fixed brackets, one of which includes a base and parallel vertical side bars rising therefrom, a pair of parallel horizontal bars extending between said brackets and contacting with the inner sides of said side bars, a wheel mounted between said horizontal bars, means pivoting said horizontal bars to said side bars, a transverse bar secured to the base of said one bracket and having upturned ends contacting with the inner sides of said horizontal bars, and spring means associated with the other bracket and horizontal bars for yieldably controlling the movement of the latter about their pivotal axis.

3. In a truck, front and rear fixed brackets, one of which includes a base and ver-

tical side bars rising therefrom, a pair of horizontal bars pivoted to the other bracket 45 and positioned in sliding contact with the inner surfaces of said side bars, a transverse bar extending between said parallel bars and having its ends bent upwardly and secured to the latter, said transverse bar being positioned over said base, a bolt rising from said base through an opening in said transverse bar, said bolt having an abutment above said transverse bar, a coil spring interposed between this transverse bar and said abutment, 50 and a wheel mounted between said horizontal bars.

4. In a truck, front and rear fixed brackets each including a base and parallel, vertical side bars rising therefrom, a pair of 60 parallel horizontal bars extending between said brackets and contacting with the inner sides of said side bars, a wheel mounted between said horizontal bars, a pivot pin connecting the front ends of said horizontal 65 bars with the side bars of said front bracket, spacing means for said front ends of said horizontal bars, a transverse bar bent into U-shape with its upturned ends secured to the rear ends of said horizontal bars, bolts 70 passing through openings in the base of the rear bracket and in said U-shaped bar, and rising above the latter, an abutment on the upper ends of said bolts and coiled springs 75 between said abutment and said U-shaped bar.

5. A structure as specified in claim 4, said spacing means consisting of a U-shaped bar secured at its base to the base of said front bracket, the upturned ends of such U-shaped 80 bar contacting with the inner sides of said horizontal bars.

In testimony whereof I have hereunto set my hand.

CHARLES WALTER LUND.
